UNITED STATES PATENT OFFICE.

ELIZABETH C. BROWN, OF NEW YORK, N. Y.

FOLDING BED.

1,366,517.

Specification of Letters Patent. Patented Jan. 25, 1921.

Application filed October 5, 1915. Serial No. 54,137.

To all whom it may concern:

Be it known that I, ELIZABETH C. BROWN, a citizen of the United States, residing in the city of New York, borough of Manhattan, county and State of New York, have invented a certain new and useful Folding Bed, of which the following is a specification.

This invention is a folding bed, the same being intended, more particularly, as an improvement upon the structure disclosed in a prior application filed by me on Nov. 6, 1914, Serial No. 870,562.

As disclosed in the prior application, the invention embodies two mattress supporting members positioned in horizontal planes one above the other, one of said members being stationary and the other member being associated with means whereby it may be raised, lowered, and locked in said raised or lowered positions; said two members affording provision for converting a compact sized structure into a double bed at will.

In my present invention the object is to improve the apparatus of the prior application in several important particulars with a view to simplifying the structure by the omission of parts without loss of function and at the same time to retain all the desirable features in respect to the ready conversion of the structure so as to accommodate one person or two persons at will; further, to render the operation of raising or of lowering one member easy and rapid, further to retain the member to be raised or lowered securely in the position to which it may be shifted without resorting to more or less complicated locking means, and finally to obtain economy in the manufacture of the structure.

A salient feature of this invention consists of worm or spiral gearing as elements of the hoisting mechanism whereby the movable mattress-supporting member may be raised or lowered at will and at the same time said worm or spiral gearing operates to securely retain said member in the position to which it may be shifted or adjusted, thereby dispensing with separate locking means.

Another feature of some importance consists in the employment of posts for the movable member telescoping or sliding relative to the posts of the non-moving member, thereby attaining simplicity and compactness of construction.

In a preferred embodiment of the invention, the non-moving mattress-supporting member is carried by a frame, the legs of which are tubular, whereas the movable mattress-supporting member is equipped with a frame the legs of which are tubular, also, and are adapted to slide or telescope within the first named tubular legs. Said sliding legs are provided with racks, with which are meshed certain gear pinions on two transverse shafts, the latter being incased within tubular transverse tie members of the frame for the non-moving mattress member. Said transverse shafts are provided, also, with worm gears, positioned preferably centrally thereon and preferably also incased in boxings or housings attached to or forming a part of the tubular tie members. A single operating shaft is provided, the same extending through and supported by the boxings or housings, said operating shaft being provided with worms positioned in meshing engagement with worm gears of the transverse shafts and one end of said operating shaft being furnished with a suitable operating member whereby the shaft may be rotated as desired for the purpose of raising or lowering the movable mattress-supporting member.

Other features and advantages of the invention will appear from the following detailed description taken in connection with the drawings.

In the drawings,

Figure 1 is a side elevation partly in vertical section of a folding bed constructed in accordance with my invention, the full lines showing the bed in folded or collapsed condition, and the dotted lines illustrating the movable mattress-supporting member as raised a suitable height above the non-moving mattress-supporting member for the purpose of enabling the bed to be occupied by two persons.

Fig. 2 is a plan view partly in horizontal section through a part of the bed, the plane of the section being indicated by the irregular dotted line 2-2 of Fig. 1.

Fig. 3 is a vertical transverse section taken through the telescopic posts of the two bed frames, the plane of the section being indicated by the dotted line 3-3 of Fig. 1.

Fig. 4 is a vertical cross section through the worm gearing taken in the plane of the dotted line 4-4 of Fig. 2.

The lower mattress-supporting member A

is carried by a rigid frame embodying side members 10, cross members 11, 12, head posts 13 and foot posts 14, the side members 10 being united to the cross members 11, 12 by 5 fittings 15. The head posts 13 and foot posts 14 are tubular in order that the corresponding posts of the frame for the upper movable mattress member may slide or telescope within the corner posts of the frame for the 10 non-movable mattress-supporting member A. In a similar manner the transverse tie members 11, 12 of the frame for the non-movable mattress member A are hollow or tubular, as shown in Fig. 2, for the accommodation of the transverse shafts adapted to impart movement to the frame of the upper mattress-supporting member B, and, furthermore, the transverse tubular members 11, 12 are constructed with gear boxings or 15 casings 16, 17, see Fig. 2.

The upper mattress-supporting member B is attached to a frame post of side member 18 and transverse members 19 and corner posts 20, 21, said parts being rigidly united 20 together. As shown, the corner posts 13 provided for the support of the non-adjustable mattress member A at the head of the bed extend upwardly for a considerable distance above the corner posts 14 provided at 25 the foot of the bed for supporting the same frame, but, obviously, the corner posts 14 may be extended upwardly like the posts 13, or the head posts 13 may be of equal height to the foot posts 14.

30 The upwardly extending head posts 13 are provided with slots 22, and the posts 20 for the frame of the member B are housed or incased within the tubular posts 13, certain parts of the frame for said member B sliding 35 within the slots 22 of the head posts. The posts 14 for the frame of the member A are open at their upper ends so that the posts 21 forming a part of the frame for the member B may enter and slide freely within said 40 tubular foot posts 14, and thus the head and foot posts of the upper member B are adapted to slide or telescope readily within the tubular head and foot posts of the lower member A, whereby the two members A B 45 are assembled and retained in parallel relation with the member B above the member A so as to be movable with respect thereto.

The structure embodies a simple and efficient hoisting mechanism performing the 50 function also of locking the movable supporting member B in a raised position. Said hoisting mechanism comprises an operating shaft 23 and a plurality of transverse shafts 24, 25. The operating shaft 23 is preferably 55 a single continuous shaft extending lengthwise of the bed structure, substantially centrally thereof, and below the member A so as to be entirely out of the way, the respective end portions of said shaft 23 being journaled in suitable bearings afforded by the

gear casings or housings 16, 17. Near its respective end portions the operating shaft is provided with worms 26, endwise movement of the shaft relative to the gear boxings 16, 17 being precluded by the employment of 70 collars 27. One end of the shaft 23 terminates within the boxing 17, but the other end of the shaft is extended beyond the boxing 16 for the reception of a suitable operating member, such as the crank 28, the latter being detachably fitted to the protruding end of the shaft and locked thereto by means of a pin 29.

75 Each cross shaft 24 or 25 extends through one of the tubular tie members of the frame associated with member A, said cross shaft extending through one of the gear boxings 16 or 17 and through openings in the fittings 15, said shaft being journaled in said fitting 15 and in the gear boxing 16 or 17. Said shaft extends above the operating shaft 23 and it is provided intermediate its ends with a worm gear 30, the latter meshing with one of the worms 26 on the operating shaft 23, as shown more particularly in connection with 80 the left hand worm gearing and the two shafts of Fig. 4. The end portions of each transverse shaft extend through slots 31 provided in the foot posts or the head posts, said end portions of each cross shaft being provided with gears 32, the latter meshing with racks 33 provided interiorly of the tubular sliding posts forming parts of the frame for 85 the upper movable section.

90 In this connection it will be understood 100 that the tubular sliding posts of the frame for the moving section B are provided with slots 31 and with interior racks 32; that the cross shafts 24, 25 extend through the tubular members 11, 12 of the frame for the non-moving section; that said cross shafts 24, 105 25 are geared intermediate their ends to the operating shaft 23 by the worm and worm gears 26, 30, respectively; that the respective end portions of the cross shafts 24, 25 110 extend into the tubular sliding posts 20, 21 of the movable frame section, and that the end portions of said cross shafts 24, 25 are provided with gears which mesh directly with said racks 33 on the sliding posts of 115 the frame for the upper movable member B.

120 The operation of the invention will be apparent from the preceding description taken in connection with the drawings, but it may be summarized as follows: Assuming that the mattress member B is in a lowered position so as to lie close to the mattress member A, and that it is desired to raise said member B from the full line position of Fig. 1 to the dotted line position of the 125 same figure, the operator applies the crank 28 and locks the same to one end of the shaft 23. Said shaft is rotated for the purpose of imparting motion to the worms 26 which in turn drive the worm gears 30 and 130

the cross shafts 24, 25, the latter being rotated simultaneously and at equal speeds. The motion of the cross shafts is communicated by the gears and racks to the sliding 5 posts 20, 21, and thus the frame and the mattress-supporting member B are raised to the desired position. The posts 20, 21 are operated by the hoisting mechanism so as to travel at the same speed and these posts 10 slide in the tubular posts 13, 14 so as to maintain the member B in a horizontal position, thus retaining the members A, B in parallel relation. The desired form of gearing provides means whereby the upper section 15 B may be raised or lowered with very little effort on the part of the operator, but in this connection attention is directed to the fact that the worms 26 and worm gears 30 co-operate in retaining the member B in said 20 raised position, whereby the member B is locked in the position to which it may be adjusted without resorting to the employment of independent or separate locking devices. Should it be desired to lower the section 25 B into close relation to the section A, the crank is turned in an opposite direction for the purpose of operating the shafts and gears, so as to lower the posts of the movable frame member within the posts of the 30 non-movable frame member, thus enabling the member B to be brought into compact and parallel relation to the member A, whereby the bed structure presents the appearance of a single bed and takes up practically the same amount of room as the 35 single bed structure.

The parts of my invention are simple in construction, easy of operation, efficient and reliable in service, and economical of manufacture. If desired, the several parts may be detachably connected by means shown in the drawings so as to provide for packing the parts in compact relation for shipment or storage, but at the same time the parts 40 of the entire structure may be easily and quickly assembled in order to set up the bed for use.

Although I have shown a form of worm gearing as the hoisting mechanism, it is to 50 be understood that I am at liberty to use any other form of gearing such as spiral gears for performing the functions of hoisting and locking the movable section, and accordingly the same is within the scope of 55 my invention.

Having thus fully described the invention, what I claim as new, and desire to secure by Letters Patent is:

1. In a folding bed, the combination of a 60 frame provided with hollow corner posts, a stationary mattress support on said frame, a second frame provided with corner posts the latter being fitted slidably within said hollow corner posts, a movable mattress support carried by the second frame, a plurality 65

of countershafts, one at each end of the bed and each countershaft extending continuously transversely to said bed, means operatively connecting the end portions of said countershafts to the corner posts of the second frame, whereby the motion of the countershafts is communicated simultaneously to said corner posts and the second frame is adapted to hoist the movable mattress support while retaining the latter in parallelism 70 to the stationary mattress support, a single operating shaft extending longitudinally of the bed, the end portions of which operating shaft are in crossing relation to said countershafts, and worm gearing intermediate 75 said countershafts and the operating shaft, said worm gearing operating to restrain each countershaft from rotation under the load upon the elevation of said second frame.

2. In a folding bed, the combination of a 80 frame provided with hollow corner posts, a stationary mattress support thereon, a second frame provided with corner posts the latter being fitted slidably within said hollow corner posts, a movable mattress support on said second frame, a plurality of countershafts one at each end of the first frame, each countershaft being geared to two corner posts of the second frame, a single operating shaft the respective end portions of which cross said countershafts, and worm gearing operatively connecting said operating shaft with said countershafts for transmitting the power so as to equally raise the several corner portions of the second 90 frame, said worm gearing operating to restrain from rotation the countershafts under the load imposed thereon when the second frame is elevated.

3. In a folding bed, the combination of a 95 frame embodying hollow posts at its several corners and tubular cross members connecting said posts, a stationary mattress support on said frame, a second frame provided with corner posts the latter being slidable within 100 said hollow posts of the first frame, a movable mattress support on the second frame, a plurality of countershafts one at each end of said bed and incased by said tubular cross members, the end portions of each countershaft being operatively connected to two 105 slidable posts of the second frame, a single shaft running lengthwise of the bed and with its end portions in crossing relation to said oppositely positioned countershafts, and 110 worm gearing operatively connecting said single shaft with the two countershafts whereby power is applied to the several corners of the second frame for positively and 115 equally elevating the same, said worm gearing operating to restrain from rotation the two countershafts under the load imposed thereon upon the elevation of the second frame.

4. In a folding bed, the combination of a 120

frame provided with hollow corner posts and with hollow cross members, the latter having gear-housings intermediate the ends thereof, a plurality of countershafts one being incased by the hollow cross member at each end of said frame, a second frame provided with slotted corner posts fitted slidably within the hollow posts of the first frame so that the end portions of the countershafts pass through said slots, rack and gear connections between each corner post of the second frame and an end portion of one countershaft so that the power to hoist the second frame is applied equally to the

several corner portions of said second frame, 15 a stationary mattress support on the first frame, a movable mattress support on the second frame, a single shaft the end portions of which cross the two countershafts and are journaled in the gear housings, and worm 20 gearing operatively connecting the countershafts with the single shaft, said worm gearing operating to restrain from rotation the two countershafts under the load imposed thereon by the elevation of the second frame. 25

In testimony whereof I have hereunto signed my name.

ELIZABETH C. BROWN.
